PAGE 4

FIG. 4

FIG. 5

FIG. 1 is a front perspective view of a microfiche viewer showing our new design;

FIG. 2 is a front perspective view of another embodiment of our new design wherein the viewing head and support therefor are larger;

FIG. 3 is a top plan view of FIG. 1;

FIG. 4 is a rear elevational view of FIG. 1;

FIG. 5 is a right side elevational view of FIG. 1.

The rear, top and side views of the FIG. 2 embodiment are substantially similar to those of FIG. 1, except larger in the upper viewing head and head support areas.

We claim:

The ornamental design for a microfiche viewer, as shown and described.
